UNITED STATES PATENT OFFICE.

GEORGE W. LEE, OF BINGHAMTON, NEW YORK, ASSIGNOR TO FRED L. LEE, JAMES G. CLONNEY, AND LESLIE E. HOOKER, OF BINGHAMTON, NEW YORK, AND A. M. CLONNEY, OF NEW YORK, N. Y.

EXTRUDING METAL.

No. 824,875.

Specification of Letters Patent.

Patented July 3, 1906.

Application filed October 14, 1903. Serial No. 177,042.

To all whom it may concern:

Be it known that I, GEORGE W. LEE, a citizen of the United States, and a resident of Binghamton, in the county of Broome and 5 State of New York, have invented a new and useful Improvement in Extruding Metal, of which the following is a specification.

My invention relates to a method for making tubular metallic bodies of any suitable 10 metal—like aluminium, for instance—by confining a blank of cold metal against lateral extension and subjecting said blank to intense pressure under the immediate impact of a 15 fluid, by means of which fluid all of the metal contained in the blank may be extruded from the die, leaving the die free for the reception of the next blank. By this means tubular bodies may be made in very short stroke 20 presses, whereas if the fluid were not used for freeing the die a much longer stroke press, necessitating a knock-out movement, would be required, and a flange would have to be 25 trimmed away by a subsequent operation. The fluid also acts as a cushion upon the descending tool, thereby greatly prolonging the life of said tool and also greatly reducing the friction by keeping the metal in the blank from direct contact with the tool, thereby 30 making it possible to form such tubular bodies with less power than when the fluid is not used. Such tubular bodies may also by this 35 process be made with simpler and less expensive dies, no knock-out being required. In making small tubular bodies by the flowing of cold metal the use of the knock-out is a serious objection, because of the intense strain and the liability of the metal to flash as soon as the joint in the die becomes at all worn.

Means for carrying the method into practical use are illustrated in the accompanying drawings, in which—

Figure 1 is a view in elevation, partly in section, showing a die, a hammer or plunger, and a disk of metal in position to be operated upon, the hammer or plunger being in its elevated position. Fig. 2 is a similar view showing the position of the hammer or plunger in contact with the disk and showing also the result of the stroke upon the disk. Fig. 3 is 45 an enlarged plan view of the disk of metal before it is operated upon. Fig. 4 is an edge view of the same, and Fig. 5 is a view of the

same after it has been operated upon by the hammer.

The die is denoted by A. In the present 55 instance it is provided with an enlarged bore a at the top, and from this there extends centrally a smaller bore a', which is to determine the size of the pin or tube which it is intended the disk shall form under the pressure 60 exerted upon it. The die A is firmly seated in a suitable bed-piece B, from which there 65 uprise guide-arms b b' for controlling the reciprocating movement of the hammer or plunger C.

The hammer or plunger C is conveniently provided on its face with a removable head D, adapted to fit with a close sliding fit the bore a in the die and in the present instance, where it is to be converted into a tubular pin, 70 having a thin head or flange. The head-piece D is provided with a central teat d.

The disk of metal which is to be operated upon—such, for instance, as aluminium, copper, zinc, or other metal that can be successfully utilized—is denoted by E and is in the present instance provided with a central perforation e. The central perforation e is not, however, essential, but is used where the pin 75 to be formed by manipulating the disk is intended to be an open tube. The disk E is intended to fit the bore a in the die and is held by the die against lateral extension. The depth of the bore a is greater than the thickness of the disk E of metal, so that the head 80 of the hammer or plunger will enter the bore a in the die before it comes into close proximity to the disk. At or about the same time that the head D of the hammer or plunger enters the bore a in the die the end of the teat 85 d is intended to enter the perforation e in the center of the disk E, thereby closing the space between the upper surface of the disk E and the end surface of the head D of the hammer or plunger air-tight. The further downward movement of the hammer or plunger 90 will serve to compress the air above the disk E, and the pressure exerted upon the disk through the medium of the stratum of compressed air will cause the latter to flow along the wall of the smaller bore a' of the die between the exterior of the teat d and the interior of said bore.

In practice I prefer to use the compressed

air as the intervening medium between the end of the head D and the disk, and in order that the air may not escape I form the fit between the head D and the bore a as perfect as 5 may be and suitably lubricate the inner wall of the bore a to make the joint air-tight and at the same time permit the head D of the hammer to slide into proximity to the disk with as little friction as may be. I may use 10 instead of compressed air a thin layer of oil or carbonic-acid gas, and it may be that experiment will prove that it is practicable to use other fluids than those mentioned. By means of this intervening layer of compressed 15 fluid the molecules of the metal in the disk under treatment are permitted to flow without great frictional obstruction, as would be the case if the surface of the head D were in actual contact with the disk. Hence I am 20 enabled to force the metal in directions and to an extent hitherto supposed impossible.

By reducing the size and shape of the teat d and changing the size of the bore a' I may

produce a solid pin instead of a tubular one, as herein illustrated, the particular structure 25 of the pin, whether tubular or solid, not forming part of the subject-matter of my present application.

What I claim is—

The method of extruding metal from a die, 30 consisting in confining a suitable cold metal blank in the bottom of a perforated die against lateral extension, interposing fluid between such confined metal and a plunger tightly fitting the cavity of the die, and imparting movement to the plunger to force the metal through the die, substantially in the manner and for the purpose described.

In testimony that I claim the foregoing as my invention I have signed my name, in presence of two witnesses, this 7th day of October, 40 1903.

GEORGE W. LEE.
